GUN-MOUNTING.

1,302,528.

Specification of Letters Patent.

Patented May 6, 1919.

Application filed July 7, 1915. Serial No. 38,630.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Gun-Mountings, of which the following is a specification.

This invention relates to gun mountings of the casemate, pedestal or upper deck type in which the sighting apparatus and the sight setter together with the elevating number are disposed within the shield.

According to this invention we so construct and arrange the mounting that the sight setter can be accommodated on a seat arranged above the seat for the elevating number; this arrangement results in an economy of space and a consequent reduction in the diameter of the shield as compared with a mounting in which the sight setter is disposed within the shield on the same level as the elevating number.

In order that the said invention may be clearly understood and readily carried into effect, we will describe the same more fully with reference to the accompanying drawings, in which:

Figures 1 and 2 are respectively a side elevation and a plan showing in a diagrammatic manner a pedestal gun mounting constructed in accordance with our invention.

A is the pedestal, B the carriage and C the shield. D represents the seat for the elevating number and E the seat for the sight setter, both these seats being mounted on the carriage so that they move with the gun in training.

In the example shown the sight setter is arranged on the seat E in a position facing toward the rear and a suitable foot rest E' is provided. The sight setter's seat E is arranged above and somewhat to one side of the seat D occupied by the elevating number so that the sight setter is close to the shield C and does not interfere with the gun layer whose head is contiguous to the sight setter's seat. A foot rest D' is provided for the elevating number.

What we claim and desire to secure by Letters Patent of the United States is:—

1. In a shielded gun mounting, the combination with the carriage cheeks, of a seat for the sight setting number arranged contiguous to one of the gun trunnions and between one of the cheeks and the shield.

2. In a shielded gun mounting, the combination with the seat for the elevating number, of a seat for the sight-setting number arranged contiguous to one of the gun trunnions and between one of the cheeks and the shield, the said seat for the sight-setting number being arranged at a higher level than the elevating number's seat.

3. In a shielded gun mounting, the combination with the seat for the elevating number, of a seat for the sight-setting number arranged contiguous to one of the gun trunnions and between one of the cheeks and the shield, the said seat for the sight-setting number being arranged at a higher level than the elevating number's seat, and sighting apparatus arranged wholly within the shield.

4. In a shielded gun mounting, the combination with the carriage, of a seat for the elevating number attached to the carriage, a seat for the sight-setting number arranged contiguous to one of the gun trunnions and between one of the cheeks and the shield, and means for attaching the seat for the sight-setting number to the carriage so that this seat is situated at a higher level than the elevating number's seat, the sight-setting number's seat being so arranged that he faces toward the rear.

5. In a shielded gun mounting, the combination with the carriage, of a seat for the elevating number attached to the carriage, a seat for the sight-setting number arranged contiguous to one of the gun trunnions and between one of the cheeks and the shield, means for attaching the seat for the sight-setting number to the carriage so that this seat is situated at a higher level than the elevating number's seat, the sight-setting number's seat being so arranged that he faces toward the rear, and a foot rest for the sight-setting number.

6. In a shielded gun mounting, the com-

bination with the carriage, of a seat for the elevating number attached to the carriage, a seat for the sight-setting number arranged contiguous to one of the gun trunnions and 5 between one of the cheeks and the shield, means for attaching the seat for the sight-setting number to the carriage so that this seat is situated at a higher level than the elevating number's seat, the sight-setting num-

ber's seat being so arranged that he faces 10 toward the rear, and a foot rest for the sight-setting number, this foot rest being at a higher level than the elevating number's seat.

In testimony whereof we affix our signatures.

ARTHUR TREVOR DAWSON.
GEORGE THOMAS BUCKHAM.
